7 Claims

ABSTRACT OF THE DISCLOSURE

Basically, a quadruple sound output loudspeaker enclosure comprised of conventional loudspeaker enclosure components, a loudspeaker mounted to a ported baffle which is placed at an angle from parallel to the enclosure back, port baffle plates which are placed at an angle away from parallel to the enclosure baffle, a loudspeaker bridge lightly secured to the front of the loudspeaker cone, a flexible membrane or diaphragm tensioned between a fixed member and an adjustable tensioning means, and a less flexible membrane or diaphragm secured to the flexible membrane.

The present invention relates to my new and improved loudspeaker enclosure for increasing enclosure efficiency and output, and suitable for high fidelity audio reproduction.

In the accompanying drawings:

FIG. 1 is a front plan view of the loudspeaker enclosure with its front grille removed;

FIG. 2 is an inner view illustrated from the top of the loudspeaker enclosure with its top member or panel removed;

FIG. 3 is a cross section through 1—1 of FIG. 1;

FIG. 4 is a cross section through 2—2 of FIG. 1; and
FIG. 5 is an enlarged cross section through 3—3 of FIG. 2.

Referring to the drawing, the present loudspeaker enclosure is comprised of a loudspeaker 10 in FIGS. 2 and 3, a back or rear wall 11 in FIGS. 2, 3, and 4, a top 12, and a bottom 13 in FIGS. 1, 3, and 4.

The loudspeaker 10 is mounted to a ported baffle 14 in FIGS. 1, 2, 3, and 4, the front grille 15 is shown by dashed lines in FIGS. 2, 3, and 4, the carrying handles 16 and 17 are shown in FIG. 1, the glides or casters 18 are shown in FIGS. 1, 2, and 4, and the loudspeaker 10 is connected by a hookup cable 42 to a suitable jack 19 in FIG. 2.

The present enclosure also comprises of a loudspeaker bridge 20 in FIGS. 2 and 3, which is lightly secured to the loudspeaker cone 41, such as with any suitable adhesive. The said bridge 20 may be a relatively rigid T-shaped or similar member made of plastic, wood or any suitable material, employed to transmit the loudspeaker cone 41 movement to a membrane or diaphragm 21, which may be made of thin plastic, polyethylene, or any suitable material, stretched between a fixed mounting member 22 and an adjustable mounting member 23 in FIGS. 2 and 3.

Secured to the flexible membrane 21 is a second membrane or diaphragm 24 which may be made of thin material, but which is preferably slightly harder than the flexible membrane 21, such as plastic laminate, employed to transmit the loudspeaker cone 41 vibrations to all areas of the first membrane 21 as in FIGS. 2 and 3.

As illustrated in FIGS. 1 and 2, member 23, which supports and tensions the first membrane 21, is held in

2

place at one end by a fixed support 25 in FIG. 2. Whereas, the other end of the said member 23 is linked to and supported by an adjustable member 26. The adjustable member 26 may be an adjustable guitar tuning gear or any suitable adjusting means mounted and passing through an enclosure cabinet side 27, such as through a guitar tuning gear insert 28, into member 23, where a suitable pin 29 links the guitar machine gear 26 to the member 23 as in FIG. 5. Therefore, by rotating the knob 40 on the adjusting means 26 in FIGS. 1, 2, and 5, the tension upon the flexible membrane 21 in FIGS. 1, 2, and 3 may be adjusted and regulated. As in FIGS. 1 and 2, the enclosure also comprises of a second side member or panel 38.

Since the operation of a loudspeaker is readily understood in the art, its operation will not be discussed in detail, except to be understood that the cone 41 of any loudspeaker 10 will move forward and backward, assuming an instrument is connected to and played through the jack 19 in FIGS. 1 and 2.

The present loudspeaker 10 is mounted to a ported baffle 14, thus said baffle has a port hole 39 in FIGS. 1, 2, and 4, for sound refraction to pass through. Furthermore, the ported baffle 14 is not placed parallel to the front nor back of the enclosure, but rather at an angle, preferably, between two and fifty degrees from parallel to the enclosure back or rear wall 11 as indicated by 30 in FIG. 2, causing the sound refraction or background movement of the loudspeaker cone 41 to reflect sound toward and through the port hole 39, in the baffle 14, as shown by 35 in FIGS. 2 and 4.

In FIG. 4, above and below the port hole 39, in the baffle 14, are port baffle plates 31 and 32, which are placed at an angle indicated by 33 and 34, to direct the propagated sound waves back through the port hole 39. The angle of the baffle plates 31 and 32, preferably, should be between two and fifty degrees from parallel to the baffle 14, to redirect the sound waves above and below the port hole 39, in the baffle 14, back through the port hole 39. Therefore, the sound refraction of the back side of the loudspeaker cone 41 in FIG. 2 follows the path indicated by 35 in FIGS. 2 and 4.

When the loudspeaker cone 41 moves forward, the sound waves produced by the cone 41 takes the path indicated by 36 in FIG. 2. Furthermore, as the loudspeaker cone 41 moves forward, this causes the loudspeaker bridge 20, as well as the membranes 21 and 24 to be set into motion. Thus, the membranes 21 and 24 also produce sound just as does the loudspeaker cone 41, except the membranes 21 and 24 have a much larger vibrating area, and greatly increase the efficiency and output of the loudspeaker 10 in FIGS. 2 and 3.

The backward movement of membranes 21 and 24 in FIG. 2, cause sound to also take the path indicated by 36. Whereas, the forward motion of membranes 21 and 24 cause sound to move as indicated by 37 in FIG. 2. Hence, due to having both the loudspeaker cone 41 forward and backward movement, and the forward and backward movement of membranes 21 and 24 causes quadruple sound output.

The present enclosure may include an outer covering which was not illustrated. Furthermore, only one loudspeaker is illustrated, however, more than one loudspeaker may be utilized if desired.

The foregoing is considered as illustrative of the principles of the invention, further, since modifications and changes may readily occur, it is not desired to limit the invention to the exact construction, and operation described, and accordingly, all suitable modifications and equivalents may be resorted to, without falling beyond the scope of the present invention.

I claim:

- An enclosure of the character described having a rear wall, a loudspeaker mounted therein to a parted baffle which is disposed at an angle from parallel to the rear wall of the enclosure, a tensioned flexible membrane or diaphragm mounted in said enclosure and spaced forwardly from the said loudspeaker, and a bridge secured to the loudspeaker cone and contacting the said membrane.
- The invention defined in claim 1, wherein the ported baffle is mounted between two and fifty degrees from parallel to the rear wall.
- The invention defined in claim 1, wherein baffle plates are secured above and below the port hole in the baffle and disposed at an angle from parallel to the baffle.
- The invention defined in claim 3, wherein the port baffle plates are mounted between two and fifty degrees from parallel to the baffle.
- The invention defined in claim 1, wherein means coupling the bridge and the membrane comprising an

other less flexible membrane secured to the tensioned flexible membrane.

6. The invention defined in claim 1, wherein the tensioned membrane is substantially parallel to said rear wall.

7. The invention defined in claim 1, wherein the flexible membrane is tensioned between a fixed support and an adjustable support.
